UNITED STATES PATENT OFFICE.

WILLIAM H. BROOKS, OF NEW YORK, N. Y.

HYDROCARBON-FURNACE.

SPECIFICATION forming part of Letters Patent No. 293,560, dated February 12, 1884.

Application filed October 22, 1883. (No model.)

To all whom it may concern:

Be it known that I, WILLIAM H. BROOKS, a citizen of the United States, residing at New York, in the county of New York and State 5 of New York, have invented certain new and useful Improvements in Hydrocarbon-Furnaces; and I do hereby declare the following to be a full, clear, and exact description of the invention, such as will enable others skilled 10 in the art to which it appertains to make and use the same.

The object of my invention is to adapt a vapor-fuel apparatus to locomotives, boilers, and other furnaces. The construction shown 15 is particularly adapted to locomotives; but it will be obvious from the accompanying description that it is equally applicable to any boiler or furnace.

My invention consists of constructions and 20 combinations, all as will hereinafter be described in the specification and pointed out in the claims, reference being had to the accompanying drawings, in which—

Figure 1 represents a longitudinal section 25 of a locomotive having the vapor-fuel apparatus adapted thereto; Fig. 2, a vertical section on line 1 1 of Fig. 3, the retort and pipe E² being partly in section; Fig. 3, a vertical section on line 2 2, Fig. 2, showing the retort 30 partially in section; Fig. 4, a vertical section through the jackets and part of the oil-vaporizer inclosed therein; Fig. 5, a horizontal section on line 3 3, Fig. 4; Fig. 6, a horizontal section on line 4 4, Figs. 2 and 3; Fig. 7, a horizontal section on line 5 5, Figs. 2 and 3; Fig. 8, a horizontal section on line 6 6, Fig. 3; Fig. 9, a detail showing part of the dome and part 35 of the retort in section; Fig. 10, a vertical section of a furnace on line 7 7, Fig. 12; Fig. 11, a vertical section on line 8 8, Fig. 12; Fig. 12, a horizontal section on line 9 9, Figs. 10 and 40 11; Fig. 13, a vertical section of the retort and part of the vaporizer; Fig. 14, a horizontal section on line 10 10, Fig. 13; Fig. 15, a detail 45 view of the burner and its inclosing-case.

A represents the boiler-furnace; B, the fire-box; C, the retort, and D, the burner; F, the steam-dome. The fire-box B is provided with the usual grate, B', and ash-box B'', which may 50 have the usual door. The fire-box is lined with soapstone tiles, which protect the walls of the same from the intense heat of the flame.

The upper part of the fire-box is provided with an arch, B³, which forms a fire-space for the burner D. In the center of this arch is 55 an opening, b³, for the escape of the products of combustion into a chamber, B⁴, which is arched by a plate, B⁵, having openings b⁵ at the ends, so that the products of combustion will be deflected against the walls before escaping. Above this arch is a chamber, B⁶, having a large central aperture, B⁷, for the bottom of the retort C, and flues b⁶ for the escape of the products of combustion into the casing, which is arranged as follows: 60

Immediately next to the fire-box B is a space, b, which I designate as the "superheater." Inclosing this is a second jacket, forming a flue, b', communicating with the chamber B⁶ by the flues b⁶, passing the superheater b, and 70 provided with an outlet, b², connecting it with flue B⁸, into which the fire-tubes B⁹ open. 65

Between the flues B⁸ and b' is a steam-space, b⁴, communicating by part b⁷ with the space b. It will be seen that the flues and steam-space 75 inclose the fire-box on all sides, and the steam in superheater b is expanded to such an extent as to put the whole pressure through its exit-pipe B¹² into the retort C. The outer jacket of the space b⁴ is provided with openings for the ends of steam-pipe B¹⁰, and has transverse partitions b⁸, which separate the pipes B¹⁰ in pairs, so that the steam will enter 80 the top space, b⁹, through the upper pipes, and escape into the next set below, and be returned 85 to the space b¹⁰, and so on until the steam enters the space below the lowermost partition b⁸. If desired, the partitions b⁸ may be dispensed with and the pipes coupled together in the same manner as the front ends, b¹², except 90 that the lowermost pipe will open into the space b⁴, as shown in dotted lines, Fig. 2. These pipes B¹⁰ are inserted in and follow the course of the flues B⁹, as shown in Fig. 1, and receive the steam from dome F by means of 95 pipe B¹³, which is connected to the upper pipe B¹⁰ and terminates within the steam-dome. This dome is attached to an offset, f, on the top of the boiler by means of a flange, f', and bolts f'', as shown in Fig. 9. The opening in 100 the top of the boiler is provided with an annular flange, i, having perforations i', for the steam to escape from the boiler to the dome. Bolted to this flange by a flange, i'', is a cylin-

- drical casing, I, which is bolted at its lower end by a flange, i^3 , to the crown-sheet I ^{2} . Suspended from this casing I by a flange, c' , is a jacket, C', which extends through the casing 5 I to the chamber B ^{6} . If desired, the jacket may be of such size that there will be an open space extending from the top of chamber B ^{6} to the flange c' , which prevents the gases in chamber B ^{6} from escaping into the steam-space. 10 The flange c' is provided with an inwardly-extending part, c^2 , provided with a groove, c^3 , to receive the tongue c^4 of flange c^5 on jacket C ^{2} , which is suspended in the chamber formed by jacket C'. (See Figs. 9 and 13.) If desired, a third jacket, C ^{6} , may be interposed between jackets C' and C ^{2} by means of similar flanges, as shown in Fig. 4. The jacket C ^{2} contains the oil-vaporizer C ^{4} , which is formed as follows:
- 20 Attached to the bottom of the jacket in any suitable manner is a tube, C ^{5} , having a vertical partition, c^6 , which divides it into two parts. The tube is made up of sections cemented together, and each section is provided 25 with a plate having a spiral passage. Rods attached to the bottom and top plates hold the parts together. In Fig. 4 the tube is closed at top and bottom, and connected with the steam-space C' by pipe c^{10} of the top plate, c^7 . 30 The steam admitted into this plate winds its way through the passages and escapes into passage c^9 , having partitions c^{18} , which divide the passage into several smaller passages, and are formed between the inlet and outlet of plates 35 c^{19} , so that the steam entering the part c^{12} of plates c^{17} will be whirled through the spiral passages and back into the passage c^9 below the partition. The bottom plate, c^{19} , differs from the others in that the steam is drawn from passage c^9 and discharged into passage c^{14} . Below 40 this plate is a perforated plate, c^{15} , connecting with passage c^{14} at c^{16} , and discharging steam upwardly in the retort C. Beneath each plate is a perforated plate, c^{17} , which allows the oil 45 dropped from pipe E to trickle through and meet the incoming steam. The tube C ^{5} shown in Fig. 13 differs from that shown in Fig. 4 in that the steam is admitted at the bottom of passage c^9 instead of at the top, as shown in Fig. 4. The passage c^9 is partitioned off between the inlet and outlet of each plate, and the outlet of the top plate opens into the passage c^{14} , which is closed at its bottom.
- It will be seen by the foregoing that the 50 superheated steam admitted from chamber C' to the oil-vaporizer is kept constantly on the move until it makes its exit into the vapor-forming chamber. The steam admitted to these plates is drawn from the superheating-chamber b by means of pipe B ^{12} , which passes 55 through the outer jacket, C ^{2} , and opens into the space C ^{7} . If the intermediate jacket, C ^{3} , be used, it is perforated near its top, at c^{18} , on the side opposite to that in which the steam 60 enters the end c^{10} of coil c^7 , so that the steam will pass around the jacket C ^{2} to end c^{10} .

Attached to the flange c' is a cap, C ^{8} , which forms a continuation of the mixing-chamber C ^{6} . This cap projects into the dome F, and may be covered by a second cap, C ^{9} , (shown 70 in Fig. 2, and in section, Fig. 9,) which prevents the steam from the boiler reducing the temperature of the superheated steam in the mixing-chamber. This cap may be attached to the flange in any suitable manner, and forms 75 a dead-air space between the caps C ^{8} and C ^{9} . The oil-supply pipe E is brought from any suitable point, and passes through the dome and cap C ^{8} and cap C ^{9} , if it be used. The vapor-pipe E' leads from the mixing-chamber to 80 the fire-box, where it is attached to the burner D. The cylinder steam-supplying pipe E ^{2} extends from the top of the dome downwardly between the retort and dome and through the 85 boiler in the usual manner.

To the throttle-valve e is attached a rod, E ^{3} , which is curved to pass around the retort, as shown in Fig. 6. This curvature of the rod 90 relieves me of the necessity of changing the position of the throttle-valve and the location 95 of the end of the rod in the cab.

If desired, the superheaters around the firebox may be tapped by a pipe, E ^{4} , having a case, e', at its opposite end to inclose the burner for supplying superheated steam at the point 100 of combustion, as shown in Fig. 15. In front of the burner are placed a series of bricks, e ^{2} , arranged in a staggering manner, so as to thoroughly commingle the gas and steam.

The operation of the device is as follows: The 105 pipe B ^{13} is connected with a boiler in the roundhouse, and steam forced through it into the pipes B ^{10} , from whence it escapes into the superheater b through space b ^{4} and port b ^{5} . The steam escapes from the superheater to the 110 retort through pipe B ^{12} , leading to the space C ^{7} therein, and having an opening near its upper part, which is connected at c^{10} to the plate c^7 . From the plate it passes to the tube and escapes into the retort, as before explained, and 115 is taken off by the vapor-pipe, from which it escapes into the air. When the parts have become sufficiently hot, oil is admitted to the retort through pipe E, and, dropping upon the heated plates, is turned to vapor, which is 120 commingled with the superheated steam escaping through the perforated plate c^{15} , and the combined steam and vapor taken off by the vapor-pipe, which is now made to communicate with the burner G. Instead of attaching the pipe 125 B ^{13} to a boiler in the roundhouse, a fire may be started in the fire-box B, and as soon as the steam is formed open the cock b ^{13} and allow the steam to enter pipe B ^{13} and pass through the parts as above described. As soon as the 130 parts have become sufficiently heated to vaporize the oil, the fire is withdrawn from fire-box B and the door of fire-box and ash-pit B ^{2} closed against the admission of air. The burner D is then started and the heat from the flame thereof is partly confined in the fire-box, so that its walls will become thoroughly heat-

ed and superheat the steam in superheater b . The productions of combustion from fire-box B pass through opening b^3 into B^4 , and are drawn to the ends thereof by the openings b^5 , through which they escape into chamber B^6 and impinge against the bottom of jacket C' . The products of combustion then pass through flues b^6 into flue b' and heat the incoming steam in space b^4 , and escape through flue b^2 into the space B^8 , which surrounds the fire-box. From thence they pass into flues B^9 , superheating the steam in pipes B^{10} , heating the water in the boiler, and escaping through the smoke-stack.

15 It will be seen by the foregoing that the steam drawn from the dome by pipe B^{13} is superheated in pipes B^{10} , again superheated in space b^4 , and again superheated in space b . The superheated steam in the space b is expanded to its highest pitch by the flame in the fire-box, and the fuel-pressure is exerted upon the retort by connecting it with the superheater b by a pipe, B^{12} . Any water of condensation that may be formed in the superheaters b and b^4 may be drawn off through pipe b^{14} .

It will be seen by the foregoing that my retort is placed in such a position as to receive all possible benefit from the different parts of 30 the locomotive, as well as economize space. In appearance a locomotive of the form now in use will not be changed.

In Figs. 10 and 11 I show my device adapted to any ordinary furnace. The steam is forced through pipe b^{15} into the steam-space b^4 , and through port b^7 into superheater b , from whence it escapes into chamber C' by means of pipe B^{12} , which passes through cap C^8 and C^9 , if it be used down between the jackets, as 40 shown in Fig. 13.

What I claim as new is—

1. In a hydrocarbon-furnace, a fire-box entirely inclosed within a superheater, forming the walls of the fire-box, substantially as described.

2. In a boiler, the combination of a fire-box and a superheater entirely inclosing said fire-box, and divided into two parts by the smoke-flue connected with said fire-box, and having 50 inlet B^{10} , connected to the outer part, and outlet-pipe B^{12} , connected to the inner part, substantially as described, and for the purpose set forth.

3. In a hydrocarbon-furnace, the combination of a water-chamber having flues, and a fire-box connected with said flues and entirely inclosed within a superheater connected with the water-chamber, substantially as described.

4. In a hydrocarbon-furnace, the combination of a fire-box, a superheater inclosing and forming the walls of the fire-box, a flue inclosing the superheater and connected with the fire-box, and pipes connecting said superheater and the steam-space of the boiler, substantially as described.

5. In a hydrocarbon-furnace, the combina-

tion of a fire-box, a superheater inclosing said fire-box, a flue inclosing the superheater and connected to said fire-box, fire-tubes connecting said flues with the exit, and pipes passing 70 through said tubes and connecting the superheater and the steam-space of the boiler, substantially as described.

6. In a hydrocarbon-furnace, the combination of a fire-box, a superheater inclosing and 75 forming the walls of the fire-box, and a retort projecting through the superheater into the fire-box, substantially as described.

7. In a hydrocarbon-furnace, the combination of a fire-box, a superheater inclosing and 80 forming the walls of the fire-box, and a retort projecting through the superheater into the fire-box and connected with the superheater by a supply-pipe, substantially as described.

8. In a hydrocarbon-furnace, the combination of a fire-box, a superheater inclosing the fire-box, a flue inclosing the superheater, and a retort projecting through the superheater and flue into the fire-box, substantially as described.

9. In a hydrocarbon-furnace, the combination of a boiler having a steam-dome, and a retort projecting into said dome, substantially as described.

10. In a hydrocarbon-furnace, the combination of a boiler having a steam-dome, a fire-box below said dome, and a retort projecting into said dome and fire-box, substantially as described.

11. In a hydrocarbon-furnace, the combination of a boiler having a steam-dome, a fire-box below said dome, a superheater inclosing said fire-box, and a retort projecting into said dome and through the superheater into the fire-box, substantially as described.

12. In a hydrocarbon-furnace, the combination of a boiler having a steam-dome, a fire-box below said dome, a superheater inclosing said fire-box, a flue inclosing said superheater, and a retort projecting into said dome and through the flue and superheater to said fire-box, and connected with the superheater by a supply-pipe, substantially as described.

13. In a hydrocarbon-furnace, a retort having its cap inclosed within a second cap, substantially as described.

14. In a hydrocarbon-furnace, the combination of a boiler, a fire-box, and a retort, said retort projecting through the top of the boiler and into the fire-box, substantially as described.

15. In a hydrocarbon-furnace, the combination of a casing connecting the crown-sheet and top of the boiler, and a retort having a flange which rests upon the top of the boiler, substantially as described.

16. In a hydrocarbon-furnace, the combination of a boiler having a dome, a retort projecting into said dome, a steam-supply having a throttle-valve, and a valve-rod conforming to the shape of the retort and extending to the cab, substantially as described.

17. In a hydrocarbon-furnace, a vaporizer consisting of a tube divided in two vertical passages, plates having spiral passages connected with the vertical passages, and a perforated plate below said plates connected with one of the vertical passages, substantially as described.

18. In a hydrocarbon-furnace, a vaporizer consisting of a tube formed in sections having longitudinal partitions, plates having passages connected with said tube, a perforated plate for discharging steam, and means for holding the sections of the tube together, substantially as described.

19. In a hydrocarbon-furnace, a vaporizer consisting of a tube having longitudinal and horizontal partitions, coils around and each connected with said tube above and below the partitions, and a perforated plate for discharging steam, substantially as and for the purpose set forth.

In testimony whereof I affix my signature in presence of two witnesses.

WILLIAM H. BROOKS.
